UNITED STATES PATENT OFFICE.

SVEN A. HOLMQUIST, OF TACOMA, WASHINGTON.

CABINET-MAKER'S CLAMP.

1,397,961.

Specification of Letters Patent.

Patented Nov. 22, 1921.

Application filed April 11, 1921. Serial No. 460,305.

To all whom it may concern:

Be it known that I, SVEN A. HOLMQUIST, a citizen of the United States, and a resident of the city of Tacoma, county of Pierce, 5 State of Washington, have invented certain new and useful Improvements in Cabinet-Makers' Clamps, of which the following is a specification.

My invention relates to cabinet makers' 10 clamps, and more particularly to improvements in clamps of that type disclosed in United States Patent No. 1,206,639, issued jointly to W. E. Youngquist and myself on Nov. 28, 1916; the principal object of my 15 improvements being to provide a clamp that may be more easily applied to the work, and which may serve to a better advantage and in a number of capacities that could not be accomplished by the clamp as previously 20 constructed.

More specifically stated, it is the object of the present invention to provide a device of the above character, comprising a pair 25 of clamping bars that, in one position, are disposed parallel to each other and between which boards, or the like, may be clamped with their edges held tightly together for gluing, and whereby the boards are retained horizontally in line and buckling prevented 30 when the clamping pressure is applied.

Another object of the invention is to provide a clamp of the above character wherein the said paired bars may be adjusted so that one forms an extension of the other and the 35 clamping lugs may be adjusted along the same to receive a multiplicity of boards.

The clamp herein disclosed is capable of a wide range of use, but is especially useful in cabinet making for clamping panels and 40 the like in shape. It is of such a nature that it will hold two, or a multiplicity of boards, in true alinement, while at the same time it will press the edges thereof in tight engagement.

45 In accomplishing the objects of the invention, I have provided the improved details of construction, the preferred forms of which are illustrated in the accompanying drawings, wherein—

50 Figure 1 is a side elevation of my improved clamp in use, showing in dotted lines the upper clamping bar in open position.

Fig. 2 is a top view of the same.

55 Fig. 3 is a side elevation of the clamp, illustrating the disposition of the upper clamping bar when it is not in use.

Fig. 4 is a transverse section taken on the line 4—4 in Fig. 1.

Fig. 5 is an enlarged detail view illustrating the manner and means whereby the two clamping bars are connected.

Fig. 6 is a side view of the device when the parts are assembled to form an extension clamp.

Referring more in detail to the several 65 views of the drawings, wherein like reference numerals designate the same or like parts,

1 and 2 respectively, designate what I will term the lower and upper clamping 70 bars. These bars, when in the most common use to which they are put, are disposed parallel to each other in the same vertical plane. They are of substantially the same length and along their outer edges are pro- 75 vided respectively with notches 3 and 4; the notches of the bar 2 opening straight from the edge while those of the bar 1 are more of the ratchet type and open at an incline to the edge of the bar.

At one end the bar 1 has a thrust head 5 fixed rigidly thereon, and threaded through this head to extend along the upper edge of the bar 1 and parallel therewith, is a clamping screw 6 provided, at its outer end with 80 a crank 7 whereby the screw may be rotated, and at its inner end the screw is rotatably fixed to a clamping head 8 that incloses and is slidable along the bar 1. A clamping head 10 is also mounted for adjustment along the 85 bar 1 in opposed relation to the head 8, and this has a U-shaped anchoring link 11, of bail like form secured thereto by means of a bolt 12 extending through the head, with its free, closed end movable into such position that it may engage within the notches of the upper or lower bar, depending upon the way in which the device is being used at the particular time, to retain it at an adjusted position.

100 The bar 2 is connected at its outer end to the corresponding end of the bar 1 by means of a pair of links 15—15', which are disposed on opposite sides of the bars and which are fixed pivotally to the bar 1 by 105 means of a pin 16 and are attached to the bar 2 by means of a pin 17 which extends through the links and is slidable within an S-shaped slot 18 in the latter bar. The inner end of the bar 2, when the device is in 110 use as shown in Fig. 1, is connected to the corresponding end of the bar 1 by means of

a pair of spaced links 19-19' which are pivotally fixed to the opposite sides of the head 5 and, at their outer ends, have a bolt or pin 20 extending between the same which 5 is removably seated within a notch 21 in the upper edge of the bar 2. The links 15-15' and 19-19' are of the same length and when connected to the bar 2 as above described are parallel so that, in this manner, the bars 10 1 and 2 are retained parallel with each other during a clamping operation.

The clamping heads 8 and 10 have slots 23 in their upper portions within which the bar 2 may seat to be held in parallel alignment with the bar 1, and by unseating the connecting pin 20 of the links 19-19' from the notch 21 the bar 2 may be swung upwardly, as shown in dotted lines in Fig. 1, to provide for an easy removal or placing 20 of boards within the clamp.

When it is desired that the device be used as an extension clamp, as is illustrated in Fig. 6, the bar 2 is swung outwardly until its outer end abuts against the outer end of 25 the bar 1. The abutted ends are provided, one with a notch 26 and the other with a projection 27, adapted to seat within the notch to hold the ends of the bars in alignment. Before the bars are moved to this 30 position it is necessary that the connecting pin of the links 15-15' be shifted to the end of the S-shaped slot opposite that wherein it is shown in Fig. 1 so that the ends of the bars, when moved to this abutted 35 position, will then be held firmly together.

After the bars have been thus arranged, the head 10 is shifted outwardly on the bar 1 and onto the bar 2, which is the same size as the bar 1, and when in a desired position 40 of adjustment it is locked by seating the link 11 in one of the notches 4 in the bar 2. To permit this movement of the head over the links 15-15', the head is provided on each side of the slot through which the bar 45 moves with channels 30, as is shown in Fig. 4, through which the links may pass as the head is shifted outwardly.

To use the device when the extension is not needed, the heads 8 and 10 are adjusted 50 as is shown in Fig. 1, the bar 2 is raised so that the boards may be placed between the clamping heads and it is then lowered against the same and secured by the links 19-19'. The closed end of the link 11 is 55 then seated within a notch 4 of the bar 1 to lock the head 10 from sliding on the bar 1 when clamping pressure is applied.

Obviously, when clamping pressure is applied by turning the screw 6, the clamping 60 heads 8 and 10 will be forced against the edges of the boards, while the bars 1 and 2 will be pulled laterally against the sides of the boards to hold them in horizontal alignment; this being effected through the connection of the head 10 with the bar 2.

If it is not desired that the bar 2 be used, it may be swung beneath the bar 1 as is illustrated in Fig. 3, and in this position will be out of the way.

The clamp thus described has been found 70 to be very efficient in the work for which it is intended. It can be very easily applied or removed from the work and is universally adjustable to work of different thicknesses and widths. 75

I claim—

1. A clamp of the character described comprising coöperating, upper and lower clamping bars having notched outer edges; the lower of said bars having a thrust head 80 fixed at one end thereof, a clamping head slideable on the bar adjacent the thrust head, a clamping screw threaded through the thrust head and fixed to the clamping head, links pivotally connecting the bars in rigid 85 spaced relation at their outer ends, another set of links, parallel with the first set, mounted pivotally on the thrust head and detachably connected with the corresponding end of the upper bar to retain said bars in parallel relation, a second clamping head adjustable along the lower bar and an anchor link pivotally fixed to said clamping head engageable within notches of the upper bar whereby clamping pressure against the head 95 effects clamping pressure to be exerted between the bars.

2. A clamp of the character described comprising a pair of coöperating clamping bars having notches in the edges thereof, the 100 first of said bars having a thrust head fixed at the inner end thereof, a clamping head slideable on the bar adjacent said thrust head, a clamping screw threaded through the thrust head and fixed in the clamping head; the second bar being connected at one end 105 with the outer end of the first bar by paired links whereby it may be held in spaced relation when used parallel with the first bar, or in end abutment therewith as an extension of the first bar, paired anchor links mounted pivotally on the thrust head, parallel with the first named links, adapted to be detachably connected with the corresponding end of the second bar to retain the bars 110 functionally in parallel relation, a second clamping head slideable along the first bar and adapted to be moved onto and along the second bar when said bars are in end abutment and an anchor link pivotally fixed to 115 the second thrust head adapted to be seated in the notches of the second bar when said bars are used in parallel or in extended arrangement.

3. A clamp of the character described 125 comprising in combination, upper and lower clamping bars having notches along the outer edges thereof; said upper bar having a detent in its upper edge near the inner end thereof and having a slot in its outer end 130

- provided with end seats facing in opposite directions and at different distances from the end of the bar, a thrust head fixed on the inner end of the lower bar, a clamping head 5 slideable on the bar adjacent said thrust head, a clamping screw connecting the thrust and clamping heads, anchor links mounted pivotally on opposite sides of the thrust head having a connecting pin between their outer 10 ends removably seated in said bar detent, a pair of anchor links pivotally fixed to opposite sides of the lower bar at its outer end having a pin extending between their outer ends and slideable within said bar slot where- 15 by said upper bar may be anchored in parallel relation to the lower bar when said pin is seated at one end of said slot and may be held rigidly in end abutment therewith as an extension when said pin is seated in the opposite end of said slot, a second clamping head 20 slideable along the first bar and adapted to be moved onto and along the second bar when said bars are in end abutment, and an anchor bail fixed to said head adapted to be seated in said bar notches when said bars 25 are used in parallel or extended relation.
4. A device as set forth in claim 1 wherein said clamping heads have alined slots across their upper portions for receiving the upper clamping bar therein to retain it in parallel 30 relation to the lower bar.

Signed at Seattle, Wash., this 4th day of April, 1921.

SVEN A. HOLMQUIST.
